SHINGLE STAINING MACHINE

Clarence W. Kraus, Buffalo, N. Y.

Application January 12, 1937, Serial No. 120,198

8 Claims. (Cl. 91—46)

The present invention relates to apparatus for staining or similarly treating shingles and the like, and has particular relation to a relatively small and compact machine for dipping shingles 5 into a bath of stain or other liquid and then removing excess liquid from the shingles.

According to my invention, the apparatus includes means for dipping the shingle and means for removing excess stain, contained in a small 10 and compact unit which may be inserted in the barrel in which the stain is delivered or a similar container, so that such barrel serves as the dipping tank. The apparatus is relatively light in weight and may therefore be moved readily from 15 one barrel of stain to another, as when it is desired to use stain of a different color, or the apparatus including the container may be rocked as a unit to agitate and mix the liquid therein.

My invention contemplates a device having 20 means for gripping shingles, carrying them down into the bath of stain and then returning them, the gripping means automatically releasing upon the return, and the means preferably being arranged so that one shingle is being carried downwardly as another shingle is returning. Brushes 25 are provided above the bath for removing excess stain from the shingles during the return stroke.

These and other objects and advantages will 30 become apparent from the following description of the typical embodiments of the invention shown in the accompanying drawings, wherein:

Fig. 1 is a perspective view of one form of the apparatus;

Fig. 2 is a view of the device in side elevation 35 with parts broken away on different vertical planes to expose the interior construction;

Fig. 3 is a vertical sectional view taken at right angles to Fig. 2;

Fig. 4 is a fragmentary vertical sectional view 40 of a portion of the mechanism shown in Fig. 3;

Fig. 5 is a side elevational view of a modified arrangement having a power drive;

Fig. 6 is a side elevational view, partly in vertical section, illustrating a modified embodiment 45 of the invention;

Fig. 7 is an end elevation, partly in vertical section, of the device shown in Fig. 6; and,

Fig. 8 is a perspective view of an element of the device shown in Figs. 6 and 7.

As shown in Fig. 1, the shingle staining unit 11 is inserted in a barrel or similar container 12 which may contain stain, and in fact may be the container in which such stain is delivered. The unit 11 may have side walls 13, end walls 55 14 and bottom wall 15. The upper ends of the

side walls terminate in inwardly directed portions 16, which merge into outwardly extending horizontal walls 17, the latter joining upper side walls 18.

Within the frame thus formed are a laterally spaced series of inverted U-shaped rods 19, the vertical legs 21, of which are spaced inwardly from and are substantially parallel to side walls 13. The bight portion 22 of each rod is in approximately the horizontal plane of walls 17 and merges into legs 21, by the curved portions 23, that extend toward inwardly deflected portions 16 of the side walls. The rods have eyes 24, at the lower ends of legs 21, the eyes receiving and being supported upon horizontal rods 25, that extend between walls 14. The curved portions 23 at the upper ends of rods 19 engage horizontal rods 26, which likewise extend between walls 14.

Upper and lower shafts 27 and 28 are journaled 20 in bearings 29 and 31, secured to end walls 14. To the shafts are secured upper and lower sprocket wheels 32 and 33 respectively, upon which are carried endless chains 34, each chain 34 being adjacent one end wall 14. Corresponding links 35, 35 of the two chains have ears to 25 which are secured eyes 37 at the ends of horizontal pivot pins 38. Links 36, 36, on the opposite sides of the chains from links 35, 35, likewise have ears to which are fastened eyes 39 that 30 are formed on the ends of pivot pin 41.

Pivoted to pin 38 is a pair of clamp members 43, and pivoted to pin 41 a pair of similar clamp members 44, the members of each pair being pressed toward each other by a plurality of 35 torsion springs 45. It will be seen that as the shaft 27 is rotated in a clockwise direction (as the device appears in Fig. 3) the left side of the chains, including links 35 and clamp members 43, will move upwardly; and clamp members 44, carried by links 36, downwardly, counterclockwise movement of the shaft will effect an opposite movement of these parts. During both movements, clamp members 43, and 44 are guided and retained substantially upright (although 45 freely pivoted to rods 38 and 41) in the channels between the side walls 13 and adjacent upright portions 21 of rods 19.

At the upper end of each such channel, and secured to each end wall 14, is a block 46, preferably having a wedge shaped lower portion 47 and parallel upper side walls terminating in shoulders 48, 48 which serve as stops. The blocks are in the paths of the end or finger portions 49 of the clamp members, so that as 55

the latter move to their upper limit positions (wherein portions 49 of the clamp members abut shoulders 48, 48) the fingers 49 will engage and be spread apart by the wedge 47 against the resistance of spring 45. In this opened position of the clamp or shingle gripping members the end of a shingle may be inserted by the operator between the clamp members.

Resting upon horizontal walls 17 are brush bodies 51, having inwardly directed bristles 52. Similar brushes 53 but with outwardly directed bristles 54, rest upon the bight portions 22 of rods 19. Each brush body has extending from each end thereof a threaded shank upon which is threaded a wing nut 55, the shanks extending through slots formed in each end wall 14. The slots 56, for receiving the shanks extending from brushes 51, are downwardly and then inwardly directed while the slots 57 for the shanks protruding from brushes 53 are downwardly and then outwardly directed.

In operation, with the unit 11 in a container 12 of stain or other liquid with which shingles are to be treated, the shaft 27 may be rotated in a clockwise direction until clamp members 43 are in their uppermost position and have been spread or opened by wedge 47. For enabling such operation the shaft 27 may have a wheel 58 provided with handle 59. Upon the clamp members 43 being spread or opened a shingle 61 may be inserted therebetween, the operator moving the shingles downwardly between opposing brush bristles 52 and 54 until the end of the shingle engages or approaches pin 38. The handle may now be turned in the opposite or counterclockwise direction, causing the clamp members 43 to move downwardly, during which motion their ends 49 will pass beyond wedges 47 allowing the springs 45 to close the clamp members, thereby causing the latter to grip the shingle 61 and carry it downwardly into the liquid in container 12.

Continuation of this movement will bring clamp members 44 to their upper limit positions 45 wherein they are spread or opened for the reception of another shingle. After insertion of the latter the handle 59 is again moved in a clockwise direction, lowering clamp members 44 and the shingle carried thereby, and raising clamp members 43 and shingle 61. During the latter part of this movement the shingle 61 will be moved upwardly between the opposing bristles 52, 54, causing excess liquid to be wiped from the upper end and then from the sides and edges of the shingle and spreading the liquid evenly over the surface of the shingle, and opening the clamp members 43 so that the shingle may be removed by hand, which completes the wiping operation, and another shingle inserted. 60 Then, upon rotation of the handle in the opposite direction the shingle carried by clamps 44 will be raised and wiped of excess liquid.

The brushes 51 and 53 which are held by clamping of the wing nuts 55 against the end walls 14, may be adjusted in the horizontal portions of the slots 56 and 57 as wear occurs by loosening wing nuts, or they may be removed for cleaning or replacement by upward movement as permitted by the vertical portions of the slots.

In the arrangement shown in Fig. 5 a motor 62 drives the shaft 27, the motor being geared to a reversing gear 63 having a driven shaft connected by pulley 64 and belt 65 to the wheel 58. The reversing gear may have a convenient-

ly located handle 66 or other suitable manual or automatic control whereby the shaft 27 may be caused to rotate in one and then the other direction or to stop. Slippage of the belt 65, or a slip clutch associated with the reversing gear, 5 may be provided to prevent damage to the machine should the drive continue to operate without immediate reversal after the clamp members have reached a limit position.

In the embodiment of the invention shown in Figs. 6, 7 and 8, the side walls 71 have outwardly and thence return bent flanges 72 and 73, and the end walls 74 extend upwardly beyond the side walls for retaining a metal frame 75 which holds brushes 76 and 77. The end walls of frame 15 75 have horizontal slots 78 which pass threaded fasteners for holding the brushes and enable horizontal adjustment of the brushes, i. e., enable adjustment of brushes 76 and 77 toward or away from each other. The frame 75 has secured thereto bolts which extend through vertical slots 79 in the upper edges of end walls 74, and by loosening wing nuts 81 threaded to these bolts the frame 75 and the brushes therein may be removed as a unit. 25

Parallel to and spaced from side walls 71 to form guides for shingle gripping members are inner walls 82, the upper ends of which are anchored to angle bars 83. The shingle gripping members comprise a plurality of clamps 84 (Fig. 8) secured to a cross bar 85 carried by an endless chain 86. The latter is supported upon and operated by upper and lower sprocket wheels 87 and 88, respectively, secured to transverse shafts 89 and 91 journaled at their ends in 30 bearings carried by end walls 74. One bar 85 is disposed adjacent each side wall 71, and the two bars are secured to opposite links of chain 86 so that one will rise as the other lowers.

Each shingle gripping member 84 comprises a 40 pair of plates 92 constituting clamping jaws, having their upper ends pressed together by a spring 93 of loop form. Each plate has a finger 94 extending downwardly through a slot in the spring 93 and thence upwardly and outwardly, 45 the fingers engaging angle members 95 and 96, respectively secured to walls 71 and 82, when the gripping members are raised to their uppermost positions, as shown in Fig. 7. This engagement causes the fingers to move outwardly from the spring 93, opening the clamping jaws against the resistance of springs. As shown in Fig. 6, 7 and 8 a plurality of gripping members 84 are held to each bar 85 by a strap 97 secured to the bar by fasteners 98. 50

Preferably disposed above shaft 89 is shaft 99 having a handle 101 for operating the device, the shafts being connected by a pulley and belt drive. The pulley wheel on shaft 99 is preferably larger than that on shaft 89 so that one turn of the handle 101 will suffice to raise one bar 85 from its lowermost to its uppermost position. 55

The device operates in substantially the same manner as the device shown in Figs. 1 to 4 inclusive, shingles inserted between jaws 92 when raised being gripped by action of springs 93 as the jaws are lowered and the fingers 94 leave angle members 95 and 96. The shingles are lowered into the stain or other liquid bath upon continued rotation of the handle and upon reverse rotation are raised and moved between the bristles of opposing brushes 76 and 77 for removal of excess liquid. 70

It will be understood that the device shown in Figs. 6, 7 and 8 may also be driven by the power. 75

drive means similar to those shown in Fig. 5, or by other suitable drive means, instead of by the handle 101.

It will be understood further that the devices shown in Figs. 1 to 4 and 6 to 7, inclusive, may be made small and light enough to permit an operator to rock the unit, including the device and the fluid container in which it is mounted, for the purpose of agitating and mixing the liquid in the container in instances where the same may be desirable. Or, if the container 12 is of the usual round type, as illustrated, I have found that the unit 11 may be spun around in the container with the effect of thoroughly mixing the liquid therein.

I claim:

1. In a shingle treating machine, a pair of substantially upright guide means, shingle gripping means slideable in said guides, means for raising and lowering the gripping means in one guide means and for simultaneously lowering and raising the gripping means in the other guide means, means for causing said gripping means to release upon approaching the uppermost position thereof for receiving or releasing shingles, and brush means mounted above said guides for removing excess liquid from shingles passing upwardly therethrough.
2. In a shingle treating machine to be placed in a container of liquid, shingle gripping means, means for lowering and raising said gripping means for causing a shingle carried thereby to be dipped in the liquid, and brush means disposed above the level of liquid in the container and in alignment with the path of movement of the gripping means for removing excess liquid from a shingle upon raising of said gripping means.
3. In a shingle treating machine, to be placed in a container of liquid, shingle gripping means, means for lowering and raising said gripping means for causing a shingle carried thereby to be dipped in the liquid, and means for causing said gripping means to release upon approaching the uppermost position thereof.
4. In a shingle treating apparatus, a container of liquid, shingle gripping means, means for lowering and raising said gripping means for causing a shingle carried thereby to be dipped into the liquid, means for causing said gripping means to release upon approaching the uppermost posi-

tion thereof, and means disposed above the level of said liquid for wiping liquid from a shingle as the latter moves upwardly after immersion in said liquid.

5. In a shingle treating machine, an endless chain movable in an upright plane and horizontally extending members connected to the chain on opposite sides thereof, means for driving the chain in either direction whereby one member will rise while the other lowers and vice versa, 10 spring pressed clamp members carried by each of said horizontally extending members, cam means adjacent the clamp members in the upper positions of the latter, and said clamp members having portions engaging said cam means for opening thereby when approaching the upper positions thereof.

6. In a shingle treating machine, endless chain means movable in an upright plane, shingle clamp means normally closed by spring means and secured to said chain means on opposite sides thereof whereby the clamp means on one side of the chain will rise as the clamp means on the other side lowers, means for operating said chain means in reverse directions, and cam means for engaging said clamp means when the latter approach the uppermost positions thereof, for opening said clamp means against the resistance of the spring means.

7. In a shingle treating machine, upper and lower wheels, an endless flexible member carried by said wheels, shingle clamp means normally closed by spring means and secured to said flexible member whereby the clamp means will rise as said wheels rotate in one direction and lower as the wheels rotate in the opposite direction, means for rotating one of the wheels in both directions, and means for opening said clamp means to receive or release a shingle when the clamp means approaches an upper position.

8. In a shingle treating machine associated with a container of liquid, shingle carrying means, means for raising and lowering said carrying means for dipping a carried shingle in the liquid, and means disposed above the level of the liquid in the container and in alignment with the path of movement of the shingle after the dipping operation for removing excess liquid from the faces of the shingle.

CLARENCE W. KRAUS. 50
